MECHANICAL ARTIFICIAL HAND

John Harold Simpson, County Down,
Northern IrelandApplication January 20, 1947, Serial No. 723,113
In Great Britain January 31, 1946

6 Claims. (Cl. 3—12)

1

This invention relates to artificial hands and more particularly to such hands for use by a wearer who only has the stump of the arm remaining above or below the elbow.

Such artificial hands are known in which the fingers are articulated and pivotally mounted on a palm part in turn mounted on a sheath, bucket or the like for attachment to the wearer's stump. A compensating linkage is mounted in the palm part and connected to the articulated fingers while a ratchet device mounted on the palm part or sheath, bucket or the like is provided and operatively connected to the ratchet mechanism, the arrangement being such that the wearer by moving another part or parts of his body operates the ratchet device through the harness and thus actuates the compensating linkage to open or close the artificial hand or cause the fingers to grasp objects while by another movement of the wearer's body the closed or gripping fingers are opened or the ratchet device is released so that the fingers open freely and rapidly under the action of a spring or other means.

The compensating linkage is arranged so that when one or more fingers engage a part or parts of an object to be gripped, the other fingers continue closing until they engage another part or parts of the article or are fully closed.

The object of the present invention is to provide an improved mechanical artificial hand of this type which will be of simple construction having the minimum of working parts and which will be easy to operate and will resemble a natural hand in appearance and operation.

Operating means according to the present invention are provided whereby when the fingers are stopped from moving forward by the object to be gripped but, at the same time, the pawl is not firmly engaged by a tooth of the rack, further relative movement of the rack with respect to the compensating linkage against an increasing force is provided, thereby to allow the pawl to engage the next tooth of the rack and to increase the grip exerted by the fingers.

The said operating means is preferably contained within the hand, and controlled by harness secured to the wearer's body and connected to the artificial hand by flexible movement-transmitting mechanism such as a Bowden cable; the arrangement is such that movement of the wearer's shoulder or other part of body operates the artificial hand. The shoulder operating mechanism and the belt are preferably interconnected and both adapted to operate one or

2

more flexible transmitting mechanisms such as Bowden cables to operate the hand.

To enable the invention to be more fully understood it will now be described with reference to the accompanying drawings in which:

Fig. 1 is a view showing a right hand of a construction according to the invention, with the thumb omitted;

Fig. 2 is a longitudinal cross-section through the forefinger of the right hand shown in Fig. 1 indicating in dotted lines the position of the forefinger when the hand is closed;

Fig. 3 is a view of a form of harness adapted for use with a left hand similar to the right hand shown in Figs. 1 and 2 as applied to a wearer having no natural left hand, and seen from the wearer's front;

Fig. 4 is a front view of a detail shown in Figs. 1 and 2, drawn to a larger scale; and

Fig. 5 is a side elevation of Fig. 4 looking from the right in that figure.

Referring to Figs. 1—5 the artificial hand shown therein is formed to approximately the shape of a natural hand with four independent fingers 1—4 and a thumb (not shown). Each finger is pivoted at its root 7 to the palm part 6 and is provided with a joint 8 in the central portion thereof; the top or outer finger joint is omitted and the tips may be straight or crooked to any desired angle.

The finger root joints are all formed by a common pivot pin 209 and the central joints 8 are formed by separate pivot pins 209a. The finger roots are formed with a central slotted portion 210 and are cut away at 211 to fit into slots 212 in the palm part 6. The cut-away portions 211 are bored to form a journal for the pin 209 and the finger roots and palm part are shaped so as to allow the fingers to rotate about the palm part to close the fingers in a gripping action.

The joints 8 are formed in a similar way to the joints 7 except that there is a separate pin 209a for each finger.

45 A guide 213 is secured to the palm part 6, in which a slide 214 is adapted to reciprocate. One side of the slide 214 is provided with a series of ratchet teeth 215 and a spring urged pawl 216 pivotally mounted on the guide 213, is adapted to engage the teeth and hold the slide 214 in one of several positions. The pawl 216 is urged into contact with the ratchet teeth by a spring 217 fixed on the guide 213. The pawl 216 carries a pin 218 which extends above the guide and 50 engages a slot in a bell-crank lever 219 pivotally

mounted on the guide at 220. Thus by moving the lever 219 the pawl 216 is moved out of engagement with the teeth 215 against the action of the spring 217.

The lower finger portions are operatively connected to floating members 223 by rods 221 which are pivotally attached to the finger portions at 222 and to the members 223 by links 224, the latter forming universal joints. The members 223 are pivotally mounted on a yoke 225 in turn rotatably mounted on a pin 226 secured to the slide 214. A tension spring 227 is connected at one end to the yoke 225 and at the other end to the palm part 6 near the finger roots. An arbor 228 fixed to the guide 213 has a drum 229 rotatably mounted thereon. A fine chain, cable, wire or the like 230 is secured at one end to the drum 229 and at its other end to the yoke 225, the drum being slotted or grooved at 231 so that on rotation (in Fig. 1, clockwise) the chain 230 is wound thereon. A radial lever 232 is secured to the drum.

The outer parts of the fingers (above joint 1) are connected by rods 233 to rods 234. The rods 233 are pivoted to the finger parts at 237 and to the rods 234 at 251. The rods 234 are mounted on the pin 209 and held against movement by pin 235 fixed in the palm part 6 and passing through the rods 234. The rods 221 and 233 pass through the slotted portions 210 and 236 respectively of the finger parts. The pivots 232 and 237 are arranged eccentrically of the pivot pins 209 and 209a.

Flexible transmission-members 238 and 239 are connected to the extremities 240 and 241 of the levers 232 and 219 respectively, and are provided with hooks or the like (not shown) at their free ends.

The yoke 225 is bored at 242 (Figs. 4 and 5) to receive the arbor 226, the boring being elongated at 243. A rubber or like resilient block 244 is inserted in the boring at one side of the arbor 226. The block 244 is curved to fit the gap between the circular arbor and the extremity of the elongated boring. A metal or like plate 245 having a curved face to engage the arbor and a flat face in contact with the rubber block may be interposed as in Fig. 5 to reduce the wear of the rubber block.

Referring to Fig. 3 the harness comprises a flexion thong 50 ending in the sheath 15 with a hook 246 and is adapted to be connected under tension to the flexible transmission-member 239: also the casing of the Bowden cable 47 or like flexible transmission member is anchored at 247 to the link 44 and the inner cable 248 is extended and connected to the D-shaped member 249 on the shoulder loop 41. The other end of the Bowden cable casing is anchored to the sheath 15 and the inner cable ends in a hook or the like 250 adapted to be connected without any slack to the free end of the flexible transmitting-member 238.

To operate the hand, the wearer raises the right shoulder thereby pulling the cable 248 and through the flexible transmission member 238 rotates lever 232 to pull chain 230 and yoke 225 wristwards against the action of the spring 227. The pawl 216 rides over the teeth 215, but by successively re-engaging each tooth under the action of spring 217, holds the slide against the returning action of spring 227. Wristward movement of yoke 225 and with it the floating members 223, pulls the rods 221 which being eccentrically mounted on the fingers at 222 causes the

lower parts of the fingers to rotate in hand-closing direction. Because of the eccentric mounting of the rods 233 the upper finger portions as they move with the lower finger portions, also rotate about said lower finger portions to simulate the complete closing or clenching movement of a natural hand.

When it is desired to re-open the closed or semi-closed artificial hand, flexing of the wearer's body will cause the flexion thong 50 to pull the flexible transmitting-member 239 and thereby move the lever 219 to disengage the pawl 216 from teeth 215 so that the yoke 225 moves away from the wrist under the action of spring 227 to open the hand again.

If during the closing movement one or more of the fingers 1-4 engages an object, further pull on the member 238 will increase the grip on such object while the remaining fingers continue closing since yoke 225 will rotate on arbor 226 and the members 223 will rotate about the yoke 225 and rods 221.

If the hand has been fully closed with or without gripping an object, the grip may not be strong because pawl 216 having traversed only part of the succeeding ratchet tooth will not trip over said tooth and moves back to the preceding tooth. An extra raising of the wearer's right shoulder will then cause the arbor to compress the block 244 since yoke 225 cannot move further, thereby causing teeth 215 to move a small distance past the pawl 216 and allow the pawl to engage the succeeding tooth and effect an added grip of the fingers.

While movement of the lever 219 to release the pawl 216 has been described as being effected by action of the flexion thong, it may be effected through suitable addition to the harness, by movement of other parts of the wearer's body, with or without the employment of a flexion thong.

The length of the levers 232 and 219 may be varied as desired; or the levers may be replaced by any suitable mechanism. The spring 227 may be arranged to operate in compression and may consist of a spring steel helical spring, or any other form of spring; or a rubber or other resilient member may be employed.

The adjustable wrist means 17-23 and thumb means 25-34 are adapted normally to be operated by the wearer's other hand.

The artificial hand may be made up of a suitable combination of light metal parts and plastics or other suitable materials for example, acrylic resins or polyvinyl chloride and the palm or other parts, such as the finger tips may have suitable rubber or flexible plastic or like pads.

I claim:

1. An artificial hand comprising a palm, fingers articulated on said palm, a guide secured to said palm and having a spring pressed pawl, a slide confined within said guide, a ratchet on said slide, finger actuating means between said slide and said fingers, resilient means between said finger actuating means and said slide, and slide actuating means secured to said palm whereby when the fingers are stopped from moving forward by an object to be gripped further relative movement of said ratchet with respect to said pawl against the increasing force is provided to allow the pawl to seat behind the next tooth of said ratchet and thereby to increase the grip exerted by said fingers.

2. A mechanical artificial hand comprising a palm part, a finger root joint comprising a com-

mon pivot pin, fingers pivotally attached to said palm part by said pivot pin forming an axis of pivot for said fingers, a guide carried by said palm part having a channel way therein coplanar with the axis of pivot of said fingers, a slide reciprocatingly carried in said channel, retaining means for holding said slide in said guide, link means for joining pairs of adjacent fingers, an equalizer block for said link means secured to and movable with said slide for simultaneously opening and closing all of said fingers, spring means for normally biasing said equalizer block and fingers to the fully extended position, means for drawing said fingers to a closed position, and latch release means for releasing said fingers from a closed position, to the fully extended or open position.

3. An artificial hand as claimed in claim 1 characterized by the fact, that said retaining means comprises a ratchet rack carried by the slide into which a spring biased pawl carried by the guide is engaged.

4. An artificial hand as claimed in claim 2 wherein said link means consists of two triangular links pivoted to the equalizer block at their 25 apexes and having finger actuating rods at their base angles.

5. An artificial hand as claimed in claim 1 characterized by the fact that said latch release means is a bellcrank arm pivoted on said guide 30 with the shorter arm positioned to contact and

disengage the retaining means and the longer arm adapter to be actuated for pivoting said bellcrank arm and releasing the ratchet mechanism and allowing the fingers to extend to their fully extended position.

6. An artificial hand as claimed in claim 2 wherein said means for drawing the fingers to the closed position is a drum rotatably carried by said guide having a chain one end of which is connected thereto and the other end of which is connected to the equalizer block, said drum being actuated by a pivoted lever.
